UNITED STATES PATENT OFFICE.

FRED FERRAND, OF SOUTHPORT, ENGLAND.

MACHINE FOR SPINNING OR DOUBLING YARNS AND THREADS.

Application filed December 9, 1922. Serial No. 605,814.

To all whom it may concern:

Be it known that I, FRED FERRAND, a subject of the King of Great Britain and Ireland, and a resident of Southport, in the 5 county of Lancaster, England, have invented certain new and useful Improvements in Machines for Spinning or Doubling Yarns and Threads, of which the following is a specification.

10 This invention has reference to machines for spinning or doubling yarns and threads, and to machines wherein the yarn or thread is spun or doubled and wound on a spindle by the rotation of a positively-driven ring 15 surrounding the spindle, which latter is rotated by the pull of the yarn or thread and is given a reciprocal travel to build up the wound yarn or thread into a cop or bobbin.

In machines of the kind referred to, it has 20 already been proposed to automatically control the speed of the spindle by means of balls acting centrifugally in conjunction with discs mounted or fixed on the spindles and with surrounding stationary sleeves, 25 and by means of pressure devices acting upon said balls. In operation, the balls acted alone during the formation of the bottom end of the cop, and as the latter was enlarged the pressure devices came gradually 30 and successively into action upon the balls which were loosely mounted upon the discs.

The main object of this invention is to provide improvements in spindle control mechanism whereby the speed of the spindle 35 can be automatically controlled entirely by the centrifugal action of balls from the commencement of the formation of the bottom of the cop or the like to the completion of the finished cop or the like.

40 According to this invention, the balls are so mounted on or in a disc or the like on the spindle that while they co-act under centrifugal force with a stationary part surrounding the spindle, they are constrained 45 to move only in radial paths relatively to the disc or the like and are compelled to rotate therewith about the axis of the spindle.

In the accompanying drawings:—

Fig. 1 illustrates in vertical section one 50 embodiment of the invention; Fig. 2 is a plan on the line 2—2 in Fig. 1; Fig. 3 is an elevation at right angles to Fig. 1; and Fig. 4 illustrates in vertical section a further embodiment of the invention.

Referring first to Figs. 1, 2 and 3, 6 is a ring mounted in ball bearings in a fixed rail 7 and through which extends the spindle 8 which is rotatably mounted in a coppering rail 9. The ring 6 has an unobstructed internal diameter sufficient to allow the cop 10 which is built up on the spindle, to pass through it.

The ring 6 is mounted in the fixed rail 7 so as to extend both above and below the same, as shown. Above the rail, the upper end 6^a of the ring is of conical formation and is formed with diametrically opposite lugs 11 provided with eyes 11^a for leading the yarn to the spindle 8 and into which the 70 yarn is passed by slits 11^b. Below the rail 7 the lower end of the ring is provided with a whorl 12 whereby the ring is driven from a pin roller as in an ordinary ring frame.

The coppering rail 9 is given a vertical reciprocation and progressive descent by means of mechanism similar to that employed for operating the ring rail of an ordinary ring frame.

The spindle 8 is mounted in a bracket 13 secured to the coppering rail 9 and provided with a footstep 14 for the lower end of the spindle and with a cap 15 which is formed with a sleeve 15^a for the support of the spindle which passes therethrough. At the level 80 of the upper part 16 of the bracket 13 the spindle has formed or mounted on it a disc 17 wherein is formed a plurality of equally spaced radial recesses 18 for the reception of steel balls 19. The recesses 18 preferably 90 incline outwards to a slight extent so that the balls 19 when inserted therein roll towards the spindle.

In operation the yarn is passed into one or other of the eyes 11^a accordingly as twist-way or weft-way yarn and cops are to be produced and the direction of rotation of the ring 6. The yarn is spun and wound on the spindle 8 by the positive rotation of the ring 6 and the cop 10 is built up by the 100 vertical reciprocation and progressive descent of the coppering rail 9 and spindle 8, which latter is rotated by the pull of the yarn.

As the spindle 8 is rotated by the drag of the yarn the balls 19 in the recesses 18 are thrown outwards by centrifugal force and bear against the inner surface of the upper part 16 of the bracket 13 and impose on the 105 spindle a retardation dependent upon the 110

speed of the spindle which varies according-
ly as the yarn is wound upon the tapered
nose of the cop. The balls 18 thus control
the speed of the spindle and prevent same
5 over-running as the yarn or thread passes
from the base of the nose of the cop to the
tip thereof.

The number of the balls 18 and the weight
thereof may be varied according to the
10 counts of the yarn or thread.

For further adapting the spindle for vary-
ing counts of yarn or thread the spindle
may be weighted by balls 20 which may
conveniently be placed in recesses 21 formed
15 in the upper face of the disc 17 and of suffi-
cient depth to prevent the balls from being
thrown outwards by centrifugal force. The
number and weight of those balls may also
be varied as found necessary.

20 In the embodiment of the invention illus-
trated in Fig. 4 the spindle 8 has mounted
on it at the lower part of its taper a dished
or concaved disc 22. The disc 22 has formed
25 in it any appropriate number of radial
grooves 28 in which, or in some of which,
the balls 19 are arranged. In conjunction
with the disc 22 is provided a surrounding
stationary casing 26 furnished with an in-
30 ternal circumferential groove 27. In operation
the balls 19 travel up the radial
grooves 28 under the action of centrifugal
force and enter the circumferential groove
27 in the casing 26 and press against the
35 casing according to the speed of the spindle
while they are carried round by the disc
22, the pressure of the balls against the cas-
ing imposing a corresponding retardation
upon the spindle.

Above the casing 26 I arrange a cover
40 29 through which the spindle 8 passes
and which may rest on the casing and be
provided with a bearing 30 for the spindle.

The lower end of the stationary casing
45 26 is mounted on or in the coppering rail 9 and
is provided with a footstep bearing 31 for
the lower end of the spindle. Below the
concaved disc 22 I mount on the spindle
50 a second concaved disc 32 which may be
stationary or may rotate with the spindle
and on which I may place one or more balls

20 of varying weights to adjustably weight
the spindle to adapt it to the spinning or
doubling of yarns or threads of varying
counts. The concavity of this disc 32 is
such that at all times the ball or balls 20
55 is or are in contact with the spindle.

Instead of the coppering rail 9 and spindle
8 being given a progressive descent, they
may be given a progressive ascent, in which
case the cop will be built up on the spindle
60 downwards instead of upwards.

The improved spindle control means de-
scribed are equally applicable for use in the
doubling of spun yarns or threads and in
the combined operations of spinning and
65 doubling, as in spinning alone.

I claim:

1. In machines for spinning or doubling
yarns and threads, a spindle, a member car-
ried by and rotating with the spindle and
70 having radial guides, balls running in said
guides in a radial direction under centrifugal
force, and a relatively stationary ele-
ment surrounding the member and with
which the balls engage to frictionally retard
75 the rotation of the spindle.

2. The machine substantially as set forth
in claim 1 in which the guides of said mem-
ber are inclined downwardly toward the
spindle so as to cause the balls to travel
80 toward the spindle and away from the rel-
atively stationary element when the speed of
rotation of the spindle falls below a certain
rate.

3. The machine substantially as set forth
in claim 1 in which the guides are formed by
85 grooves in the upper face of the said mem-
ber.

4. The machine substantially as set forth
in claim 1 in which the guides are formed
90 by grooves in the upper face of the said
member, said grooves being inclined down-
wardly toward the spindle so as to cause the
balls to travel toward the spindle and away
from the relatively stationary element when
95 the speed of rotation of the spindle falls
below a certain rate.

In witness whereof I have hereunto set
my hand.

FRED FERRAND.
